DESIGN FOR A SCHEDULE RECORDING BOARD

Doris E. O'Sullivan, Rockville Centre, N. Y.

Application October 3, 1940, Serial No. 95,623

Term of patent 3½ years

To all whom it may concern:

Be it known that I, Doris E. O'Sullivan, a citizen of the United States, residing at 147 Broadway, Rockville Centre, in the county of Nassau and State of New York, have invented a new, original, and ornamental Design for a Schedule Recording Board, of which the following is a specification, reference being had to the accompanying drawing, forming part thereof.

The figure is a plan view of a schedule recording board, showing my new design.

The article is of conventional thickness.

I claim:

The ornamental design for a schedule recording board, as shown and described.

DORIS E. O'SULLIVAN.
